No. 764,237.

PATENTED JULY 5, 1904.

A. R. HAGNER.

DRYING APPARATUS FOR GRAIN BINS.

APPLICATION FILED APR. 18, 1904.

NO MODEL.

UNITED STATES PATENT OFFICE.

ALEXANDER R. HAGNER, OF HAGERSTOWN, MARYLAND.

DRYING APPARATUS FOR GRAIN-BINS.

SPECIFICATION forming part of Letters Patent No. 764,237, dated July 5, 1904.

Application filed April 18, 1904. Serial No. 203,546. (No model.)

To all whom it may concern:

Be it known that I, ALEXANDER R. HAGNER, a citizen of the United States, residing at Hagerstown, in the county of Washington 5 and State of Maryland, have invented certain new and useful Improvements in Drying Apparatus for Grain-Bins, of which the following is a specification.

This invention relates to a drying apparatus for grain-bins, and has for its object to provide a device of simple construction by means of which air may be thoroughly distributed through the grain and the latter thoroughly dried.

15 The invention is illustrated in the accompanying drawings, in which—

Figure 1 illustrates a vertical section through the lower end of a bin and hopper and also through the drying apparatus. Fig. 2 is a similar view of the hopper and an end elevation of the drying apparatus. Fig. 3 is a vertical longitudinal section through the air-distributing cylinder. Fig. 4 shows an enlarged sectional elevation through the distributing-chamber and illustrates the fan device on the interior of the chamber, the section being taken on the line 4-4 of Fig. 1. Fig. 5 illustrates an enlarged detail elevation of a portion of the distributing-chamber and 30 a vertical section of one of the hopper-walls.

Referring to the drawings by letters, A designates a receptacle or bin of any suitable construction, which in the present instance is provided with a hopper a , the lower end a' of which is inwardly inclined to form a V-shaped trough. An opening a'' is provided in each inclined side of the hopper, and a sliding door a''' is provided in said side at each of said openings. Above the inclined end the hopper is 35 provided at opposite sides with a substantially circular opening b , and a bearing-plate b' is secured to the vertical walls of said hopper at said circular openings, and said plates are each provided with an opening b'' , through 40 which air may pass to the interior. A horizontal shaft c is supported at opposite ends in said bearing-plates b' , and said shaft is to be revolved in any suitable manner. A plurality of arms c' are suitably carried by said 45 shaft, and said arms support a plurality of

fan-blades c'' , which are revolved with said shaft.

A hexagonal frame comprises two end plates d , each of which has a center perforation d' and a plurality of horizontal rods d'' , which 55 connect said plates. Two flat metal stiffening-rings d''' are interposed between the end plates d and serve to keep the rods in a straight horizontal position and parallel with the shaft c . A wire sheet-screen e is wrapped 60 around the hexagonal frame and completely covers the latter from one end to the other and forms an air-distributing cylinder which surrounds the fan. By reference to Fig. 1 of the drawings it will be seen that this distributing-cylinder extends from one side of the hopper to the other and has its ends terminating in the circular openings b in the hopper-walls, and the perforations d' in the end plates d adjoin or are at the side of the openings b'' in the bearing-plate b' . By means of this arrangement air may be drawn through the openings b' and perforations d' to the interior of the distributing-chamber as the fan-blades are 70 revolved. The sheet-wire screen e is provided 75 with a plurality of laterally-projecting perforated tubular arms f , which in the present instance project from the various flat sides. These arms are preferably formed of wire-netting, and their outer ends are closed by a plug f' , from which an eye f'' projects. Hooks f''' are secured to the walls of the hopper, and each hook is attached to one of the eyes in the ends of said tubular arms and serves to support the same. The inner ends of the tubular arms 80 are open and are in communication with the interior of the distributing-chamber. When the bins and hoppers are filled with grain, the tubular radiating arms serve as branches through which the air will be conducted and 85 distributed through the grain. In order to further distribute the air through the bulk of grain, I provide a plurality of perforated tubes g , each of which connects two adjoining radiating arms f , so that the air churned up by 90 the fan will be conducted through the arms f and tubes g and thoroughly distributed 95 through the surrounding grain.

In the drawings the distributing-cylinder is illustrated as employing three sets of dis- 100

tributing-arms; but it is to be understood that a greater or less number may be employed. It is also to be understood that the device may be used for drying corn or things other than grain.

Having thus fully described my invention, what I claim as new, and desire to secure by Letters Patent, is—

1. The combination with a receptacle of a perforated cylinder in said receptacle, a plurality of perforated tubes radiating from said cylinder and a fan device within said cylinder.
2. The combination with a receptacle having openings in its sides, of a perforated cylinder in said receptacle and provided with end perforations; a plurality of perforated tubes in communication with the interior of said cylinder and radiating from the latter, and a revoluble fan device on the interior of said perforated cylinder.
3. The combination with a receptacle having openings in its sides; of bearing-plates secured to said receptacle and covering said openings and each plate having an opening for

the passage of air; a perforated cylinder extending across said receptacle and having its ends terminating in the side openings of said receptacle, said cylinder having perforated end plates adjoining the side openings of said receptacle; a shaft extending through said perforated cylinder and supported in said bearing-plates, and one or more fan-blades carried by said shaft and revoluble with the latter within said cylinder.

4. The combination with a receptacle, of a shaft extending across said receptacle and carrying one or more fan-blades; a stationary frame supported within said receptacle and surrounding said shaft and fan; a perforated covering supported by said frame, and a plurality of perforated tubes radiating from said covering.

In testimony whereof I affix my signature in presence of two witnesses.

ALEXANDER R. HAGNER.
